REVERSIBLE BRACELET

Maria Xtazy, Chicago, Ill.

Application October 21, 1957, Serial No. 48,168

Term of patent 3½ years

(Cl. D45—4)

Fig. 1 is a plan view of one side of a reversible bracelet showing my new design, the links shown in full lines being repeated throughout the length thereof as indicated by the dot and dash lines;

Fig. 2 is a plan view of the other side thereof; and

Fig. 3 is an edge view thereof. The dotted line showings of the clasp portions at the ends of the bracelet are for illustrative purposes only.

I claim:

The ornamental design for a reversible bracelet, substantially as shown and described.
